UNITED STATES PATENT OFFICE

OCTAVOUS C. GILBERT AND JOHN L. ARLEDGE, OF HATTIESBURG, MISSISSIPPI

FIRE ALARM

Application filed March 31, 1931. Serial No. 526,738.

This invention relates to an improved fire alarm in the nature of an audible signal primarily designed for home or domestic usage and intended to give a dependable warning signal when a part of the premises adjacent to the signal is on fire.

In carrying the inventive conception into practice, we have evolved and produced a simple and economical appliance which may be attached in various places in a building, particularly adjacent the chimney or other point at which a fire would most likely start from a heating system or the like.

One feature of the invention is founded on the use of a duplex or multiple cartridge explosive device of a fusible character, which is influenced to operate and give a warning signal by flame or fire impinging on either one or both of the cartridges, thereby giving a loud report to notify the occupants of impending danger.

Another innovation of the invention is a novel attaching fixture designed to mount the explosive device in spaced parallelism to the adjacent supporting surface and equipped with inflammable elements susceptible of bursting into flame readily and to thereby induce more effective and ready explosion of the warning cartridges.

In the drawings:

Figure 1 is a fragmentary view of a portion of a building showing a chimney and disclosing a plurality of the warning signals mounted at vital points.

Figure 2 is a top plan view of the complete alarm or signal.

Figure 3 is a side elevational view of the structure seen in Figure 2 with the attaching fixture or bracket in section.

Figure 4 is a longitudinal and large detail section on the line 4—4 of Figure 2.

Figure 5 is a fragmentary sectional view showing the exploded end portion of one of the cartridges.

Figure 6 is an end elevation of one of said cartridges.

Figure 7 is a cross section on the line 7—7 of Figure 3 with an explosive charge removed.

Figure 8 is a plan view or a disc or wafer ignition element.

Figure 9 is a section on the line 9—9 of Figure 8.

In the drawings, in Figure 1, we have shown a number of the warning signals or alarms in distributed positions, these being supported at vital points with the frame structure of the building and generally within the vicinity of the chimney 10. It is obvious however that the mounting of these devices is a matter which lies within the discretion of the user.

We refer now to Figure 3, showing the general assembly wherein the reference character 11 designates the supporting surface, 12 indicates the attaching fixture or bracket and 13 generally represents the double acting or duplex explosive cartridge device. This device 13 is of fusible metal and in practice it has been found practical to utilize a copper tubing. A single length of copper tubing has been found satisfactory, this being indented and pressed into substantially flat formation as indicated at 14 to permit it to be attached by a bolt 15 to the central arched portion 16 of the bracket.

The bracket, incidentally, includes extending apertured attaching ears 17 secured in place by wood screws or the like 18.

The portion of the tube extending on opposite sides of the bracket constitute cartridges or containers for an explosive powder 19 as shown in Figure 4. This powder may be of any appropriate texture and is preferably of such character as to maintain its explosive properties for an indefinite period of time and to overcome deterioration.

The end portions of the tubular cartridges 20 are flattened as indicated at 21 to form closures, these closures being such as to inhibit the entrance of moisture or air and to effect dependable maintenance of the explosive powder 19. It might be added that in Figure 5, we have shown the manner in which the companion portions of the flattened end are disrupted when the charge is fired.

We now call attention to the pre-ignition wafers or discs 22 (see Figure 8). Each disc is of a highly inflammable substance or mate-

rial and is provided with a metallic bushing 23 for reinforcing and attaching purposes. The same screws 18 which are employed for attaching the brackets serve to attach these 5 ignition wafers to the end portions 17 of the bracket.

In practice, it is obvious that the powder filled cartridges 20 of the device 13 are attached by way of the indenture 14 and the bolt 15 to the crown portion of the arch 16 of the bracket 12, as shown in Figure 3, thus disposing the device 13 in spaced parallelism to the supporting surface 11.

The bracket is attached in place by the end portions 17 and the highly inflammable ignition washers or wafers 22 are secured by the screws 18. If a fire originates within the vicinity of the device 13, it is obvious that the highly inflammable nature of the elements 22 will cause these to be set on fire, permitting the flanges therefrom as well as surrounding flames to impinge on the powder filled cartridges 20.

This will produce an explosion of one or 25 both of the cartridges, thus giving a loud audible report which will serve as a warning to the occupants of the premises that danger is impending in an obvious manner. It is believed therefore, that a device of this kind is 30 a novel contribution to the prior art, susceptible of sensitive operation and capable of fulfilling the requirements of an appliance of this kind in a highly practical and satisfactory manner.

35 It is thought that the description taken in connection with the drawings will enable a clear understanding of the invention to be had. Therefore, a more lengthy description is thought unnecessary.

40 While the preferred embodiment of the invention has been shown and described, it is to be understood that minor changes coming within the field of invention claimed may be resorted to in actual practice if desired 45 without departing from the spirit and scope of the appended claims.

We claim:

1. As a new product of manufacture, an 45 explosive warning signal of the class described comprising a length of copper tubing having its central portion depressed and flattened to form an attaching element, having its end portions flattened to provide closures and intervening cylindrical containers, 55 said containers being charged with an explosive.

2. As a new product of manufacture, an 60 explosive warning signal of the class described comprising a length of copper tubing having its central portion depressed and flattened to form an attaching element, having its end portion flattened to provide closures and intervening cylindrical containers, 65 said containers being charged with an explosive, and an attaching bracket including

a central arched portion to which the attaching portion of said tube is fastened.

3. In a structure of the class described, an attaching bracket including a central arched portion and oppositely projecting apertured 70 attaching portions, an inflammable wafer ignition element carried by each attaching portion.

4. In a structure of the class described, an 75 attaching bracket including a central arched portion and oppositely projecting apertured attaching portions, an inflammable wafer ignition element carried by each attaching portion, said wafer element including a central reinforcing and attaching bushing to accommodate the fastening element for the adjacent attaching portion.

5. A structure of the class described, an 80 attaching fixture having a central raised portion, a multiple cartridge explosive device of 85 a fusible character secured to said raised portion and overlying the end portions, and inflammable elements carried by the end portions of the attaching fixture and underlying the adjacent portions of said cartridge. 90

In testimony whereof we affix our signatures.

OCTAVOUS C. GILBERT.
JOHN L. ARLEDGE.
